UNITED STATES PATENT OFFICE.

WILLIAM C. CUTLER, OF GLENDALE, CALIFORNIA, ASSIGNOR TO ISABELLA M. CUTLER,
OF GLENDALE, CALIFORNIA.

SELECTIVE DISPENSING MACHINE.

Application filed September 16, 1925. Serial No. 56,710.

The present invention relates to selective dispensing and vending machines and has for its principal object the provision of a simple and compact machine adapted to 5 store articles of either regular or irregular shapes and sizes in such manner that any selected article contained in the machine may be had only by proper or authorized operation of the machine.

10 Another object of the invention is to provide a selective vending or dispensing machine suited for articles which are not adapted to being subjected to pressure or continual movement.

15 Another object of the invention is to provide a machine of the class described from which any selected article may be obtained without disturbing other contained articles.

20 Another object of the invention is to provide simple operating and selecting mechanism, with a view to eliminating latches, latch releases, springs, etc.

25 Another object of the invention is to provide a machine of the class described, embodying a plurality of article holders, in which machine the article holders are capable of arrangement in close juxtaposition so that no intervening space is used up or wasted.

30 Still other objects include simplicity of mechanism and low manufacturing cost and upkeep.

Further objects and advantages of my invention will appear hereinafter.

35 I have illustrated my invention by the accompanying drawings in which Figure 1 is a view in front elevation of one embodiment of my invention, Figure 2 is a view in section on a line 2—2 of Figure 1, Figure 3 is

40 a similar view showing the parts in operative position, Figure 4 is a plan view of one end of the machine, and Figure 5 is a view in section of the other end as seen on a line 5—5 of Figure 2.

45 In carrying out my invention I employ a plurality of article holders 10, each having an open outer end as at 10^a. The machine includes a casing 11 having a front wall 11^a, a bottom wall 12, a rear wall 13 and a top wall 14. In conformance with a salient feature of my invention said top wall has a solid portion 15 and an open portion 16.

The article holders are arranged side by side across the machine and each holder embodies side walls 17; the side walls of each

holder being in very close proximity to the side walls of the adjacent holders. By placing all holders close to each other the possibility of inserting any thin bladed instrument between the holders is precluded.

60 Each holder is arranged to be movable so that its outer open end may be moved from under the closed portion of the top wall into registration with the opening in said wall.

65 Various means may be employed for rendering the holders so movable but, in the embodiment shown, each holder is individually hinged to the rear wall as at 18. The holders, in the embodiment shown, are of rectangular cross section and include front and

70 rear walls 19 and 20 respectively. Being hinged at the point most remote from the front wall, the holders, especially when filled, will each incline toward the front wall by its weight and accordingly said front wall is inclined outwardly and upwardly to act as a suitable rest and stop for the holders.

75 The holders each include a bottom wall 21 so that a contained article such as 22 may be held therein. Another purpose for the bottom wall will be apparent hereinafter. The front wall is provided with a hinge 23 so that it may be swung forwardly and downwardly, and the top wall is prefer-

80 ably made integral with the front wall. It will be apparent now that the front wall may be swung forwardly and downwardly, leaving all the article holders fully exposed for inspection and refilling. The upper

85 ends of the vertical walls of each holder are disposed on an arc coaxial of the center of oscillation of the holder, and the top wall of the casing is accordingly curved. The top wall fits closely over the upper ends of the

90 article holders with just enough clearance to permit of the holders being moved, without appreciable friction.

95 The holders may each contain a single article or a plurality of loose articles and the form of holder illustrated is well adapted for holding irregular objects such as candy bars, loose articles in bags, fruit, and the like.

100 When the holder is in the position shown in Figure 2, the contents are inaccessible but may be seen thru sight openings 24, one of which is provided for each holder and which are closed collectively by a glass

105 plate 25.

110 Before the contents of any holder can be obtained it is necessary to move the article

holder so that its open end is in registration with the opening in the top wall of the casing. Various means may be employed for selectively moving any holder independently of the others, and I will now describe the specific means illustrated. Below the holders and co-extensive of the series of holders, I provide a rock shaft 27 which extends out thru an end wall 28 of the casing and carries an operating handle 29. The shaft passes thru a bearing 30 within the casing, and includes an integral thrust collar 31. Between the bearing and collar, I provide a spring 32 under considerable compression so that friction between the collar and bearing will hold the rock shaft in any position in which it is set. Just externally of the casing, I provide a small housing 33 which may contain a coin released lock (not shown) or other coin controlled means to prevent unauthorized rocking of the shaft. Numerous coin-controlled means for rendering the handle inoperative on the rock shaft without the payment of the requisite toll are well known to the art and therefore I have not illustrated or described any such means. Where the machine is to be used without payment of a toll, no such coin controlled means is required.

30 The rock shaft is provided with a groove 34 in which rides a pin 35, and said pin is carried by a cam 36. With the cam disposed below an article holder, rocking of the shaft will cause the cam to act on the bottom wall of a holder and move same into vertical position over against the rear wall of the casing. The article holders on each side are cut away as at 38, immediately above the rock shaft, so that if the cam is positioned intermediately of two holders it will not be effective on either. To selectively position the cam, which is loosely slideable along the length of the shaft, I provide a movable forked member 39. Said forked member is arranged to slide along a rod 40 and passes out thru a slot 41 in the front wall of the casing and terminates in a selecting handle 42. While the forked member will move the cam along the shaft in either direction, it will allow the cam and rock shaft to turn freely.

55 In the operation of the machine, the selecting handle is moved to dispose the cam below the article holder which contained the desired article. It will be understood that each holder may contain a different article and the number of different articles or brands to be vended by the machine is limited only to the number of holders employed. 60 When the cam is positioned, the operating lever is rocked to rock the shaft. If the machine is coin controlled, then a coin must be inserted first in the coin controlled mechanism, but it will be apparent that the selecting handle may be moved independently of

the rock shaft so that the selection may be made at any time. When the shaft is rocked, the cam will move the holder to the position shown in Figure 3 in which position the contents of the holder may be removed. 70 The friction means described will hold the shaft in any position in which it is left and thereby the holder is held in accessible position, without effort, as long as desired. No stops, limits, or return springs are used or 75 required for the operating handle and rock shaft, the moved holder being the sole limiting means. The operating handle may be left in position with the holder in accessible position, but before the cam can be moved 80 to another holder it must be turned back to original position by the same or a subsequent purchaser. When the shaft and cam are returned to normal position, the holder will drop back into inaccessible position where 85 it cannot collect dust or the like.

The machine is easily replenished as explained, and article holders are so close together and so arranged that they cannot readily be unlawfully moved to accessible 90 position, particularly when the machine is bolted down as by bolts 41.

In Figure 6 I have shown a modification in which there is provided a lip on the bottom wall of each holder engaged by a latch 95 43, so that the holders are each individually locked against movement. The cam has an additional protruding portion 44, which, when the cam is turned, first abuts and releases the latch just before it starts to raise 100 the bottom wall of the holder.

It will be apparent now that I have provided simple and efficient means for selectively vending articles and, while I have specified certain constructions, I do not limit 105 myself to any construction or arrangement of parts and may alter same as I desire without enlarging the scope of my invention within the appended claims.

Having described my invention, what I claim is:

1. In a selective vending machine, a plurality of article holders arranged in close juxtaposition in a lineal series, hinges, one for each holder hinging same in said casing so that they are independently oscillatable upon their respective hinges, each holder having its outer end open, a curved wall to said casing adapted to close the open ends of all holders; said wall conforming to an 115 arc described about the center of the hinges and closely spaced from the open ends of the holders, said casing having an open portion with which the open end of any holder will register when that holder is properly moved 120 on its hinge.

2. In a selective dispensing machine, a casing, having front and back walls respectively, a plurality of open end article holders arranged in a lineal series between said 130

walls, each holder being individually hinged in said casing adjacent the one end of the holder whereby each holder may be moved so that its upper end may rest against either 5 wall, said casing having a top wall provided with an open portion with which the open end of a holder is registered when the holder rests against one wall, said top wall also having a closed portion which covers the open end 10 of a holder when said holder is resting against the other one of the spaced walls.

3. In a selective machine of the class described, a casing having spaced parallel walls, a plurality of rectangular article 15 holders closed at the lower end and open at the upper end, and including vertical walls joining the closed end, a hinge for each holder connecting the corresponding holder hingedly to one of the spaced walls 20 of the casing at a point adjacent the intersection of the closed end and one vertical wall respectively of the holder whereby each holder may be tilted from one position to another between the spaced walls, a top wall 25 to said casing having a closed portion adapted to cover the upper open end of the article holders which are in the one position, said top wall having an open portion rendering the open ends of the holders accessible 30 when said holders are in the other of said positions.

4. In a selective dispensing machine, a rock shaft, a cam keyed to said rock shaft

to turn therewith and slidable along said shaft to any selected position, a plurality 35 of article holders each having a bottom wall hinged at a point above and to one side of said shaft so that each bottom wall thereof overlies said shaft in spaced relation in position to be raised by turning movement of 40 said cam, and means for holding each bottom wall spaced above said shaft for movement of the cam along said shaft.

5. In a selective dispensing machine, a rock shaft, a cam keyed to said rock shaft to 45 turn therewith and slidable along said shaft to any selected position, a plurality of article holders each having a bottom wall hinged at a point above and to one side of 50 said shaft so that each bottom wall thereof overlies said shaft in spaced relation in position to be raised by turning movement of said cam, and means for holding each bottom wall spaced above said shaft for movement 55 of the cam along said shaft, a casing enclosing said shaft and article holders, a top wall to said casing having an open end normally covered by the closed portion of said top wall; the open portion of the top wall being positioned to register with the 60 open end of an article holder when the bottom wall of said holder is acted on by said cam.

In testimony whereof I affix my signature.

WILLIAM C. CUTLER.
